UNITED STATES PATENT OFFICE.

CARL G. SATHER, OF SIOUX FALLS, SOUTH DAKOTA.

DISPLAY-STAND.

1,384,351.

Specification of Letters Patent. Patented July 12, 1921.

Application filed July 26, 1920. Serial No. 398,899.

To all whom it may concern:

Be it known that I, CARL G. SATHER, a citizen of the United States, residing at Sioux Falls, in the county of Minnehaha 5 and State of South Dakota, have invented certain new and useful Improvements in Display-Stands; and I do declare the following to be a full, clear, and exact description of the invention, such as will enable others 10 skilled in the art to which it appertains to make and use the same.

This invention relates to an improved display stand designed for detachably supporting forms on which apparel and other mercantile chandise is placed for exhibition.

At the present time devices of this class, many of which I am familiar with, are usually made up of a suitable base from which a standard rises. The last named part 20 in most instances is cylindrical and is in this instance made of wood, consequently, when the tubular part which carries the form is fitted thereon, it is permitted to rotate. Such rotation of the form on the upright is undesirable because often times unless the greatest care is taken the set screw which is employed for retaining the form in various adjusted positions embeds itself into the upright at a different point each time it is operated, and thus ruins the upright.

It is my intention and the object of this invention to overcome the above circumstances by providing a display stand in which the movable parts will not rotate with 35 respect to each other, this means being such that a part thereof forms a solid bearing for the usual set screw and prevents the upright from becoming marred.

Another object of the invention is to generally improve upon devices of this class by producing one of extreme simplicity which is strong, durable, highly efficient in use, easy to manipulate, and inexpensive to manufacture.

Other objects and advantages of the invention will be apparent during the course of the following description.

In the accompanying drawings forming a part of this specification and in which like numerals are employed to designate like parts throughout the same:

Figure 1 is an elevational view of a dis-

play stand constructed in accordance with my invention.

Fig. 2 is a similar view with parts broken away to disclose the construction more clearly.

Figs. 3 and 4 are horizontal sections taken on the lines 3—3 and 4—4 respectively of Fig. 1, looking in the direction of the arrows.

Referring to the drawings wherein the details of construction are clearly shown, it will be seen that the numeral 1 designates a standard which if desired, may be mounted upon a suitable base 2.

This standard is like those in use at the present time, that is, it is cylindrical and is made of wood which renders it light and inexpensive.

In accordance with my invention there is formed in one side of the standard a longitudinal groove 3, which extends from the top thereof to the point below the center.

Fitted in this groove and secured therein in any suitable way is a channel-shaped metal lining 4.

Vertically slideable on the standard is a sleeve 5 provided with an internal longitudinally extending rib 6 which is received in the aforesaid channel member 4.

To retain the sleeve in various adjusted positions, the usual set screw 7 is provided, the same being extended through the sleeve and rib so that its pointed end will engage the bottom of the member 4 which forms a solid bearing therefor and prevents it from embedding itself in the standard as it usually does.

As usual, the sleeve 5 carries an annular laterally extending flange 8 upon which the base 9 of the form 10 is detachably connected by means of bolts 11.

At this point I desire to mention that the base of the form often times works loose from the attaching flange 8, which of course, is not desirable. I provide means for overcoming these circumstances.

This means includes a collar 12 fitted on the sleeve 5 and retained in position by means of a set screw 13, the collar carries a plurality of depending brace arms 14 which are secured at their lower ends to the base 9 of the form.

This construction overcomes the above disadvantage in an effective way.

From the foregoing description it will be seen that I have perfected a display stand which is effective in use and advantageous in many respects. In support of the fore-

going statement it may be said that a stand constructed in accordance with this invention prevents relative rotation of the standard and sleeve which slides thereon, consequently preventing damaging of the upright. The means employed for carrying out the above feature is not only advantageous in itself, but it is advantageous because a part thereof, that is the metal lining of the channel, provides a solid bearing for the set screw 7 and prevents the latter from embedding itself in the standard and ruining the same in a short time as it would do with stands of this type now on the market. Another feature of construction resides in the fact that means is provided for decidedly increasing the rigidity of the devices, this means being the brace arms 14 which are such that they will permit the form 10 to be easily and readily disconnected from the flange 8 by simply removing the bolts 11 and lifting the form. My construction is simple, inexpensive, and entirely effective in every respect.

While I have shown and described my stand as being used in connection with a particular type of form, I desire it to be understood that it may be equally well used for supporting forms of various constructions and designs.

A careful consideration of the foregoing description taken in connection with the accompanying drawings will enable persons skilled in the art to which this invention relates, to obtain a clear understanding of the manner of using and construction of

the same, therefore, further description is deemed unnecessary.

I claim:

1. A display stand comprising a standard 40 provided in one side with a longitudinal groove, the bottom of which is reinforced, a form-carrying-sleeve vertically slidable on said standard, being provided with an internal rib extending into said groove, and 45 a set-screw passing through said sleeve and rib into the groove and against the reinforced bottom of the groove.

2. A display stand comprising a base, a cylindrical wood upright rising therefrom, 50 being provided in one side with a longitudinally extending groove, a channel-shaped metal lining in said groove, a sleeve vertically slidable on the upright and provided with an internal rib fitting into said groove, 55 a set-screw passing through said sleeve and rib and against the bottom of the groove, and a lateral flange carried by the sleeve for attachment of a form.

3. A display stand comprising a stand- 60 ard, a sleeve non-rotatably but vertically movable thereon, a lateral flange carried by the sleeve for detachable connection to the base of a form, a collar fitted on the sleeve, a set-screw passing through the collar and 65 against the sleeve, and a plurality of brace arms carried by the collar, the lower ends of the arm adapted to be secured to the base of the form.

In testimony whereof I have hereunto set 70 my hand.

CARL G. SATHER.
